UNITED STATES PATENT OFFICE.

HAROLD A. SMITH, OF SEATTLE, WASHINGTON, ASSIGNOR OF ONE-HALF TO JOHN F. PRATT, OF SEATTLE, WASHINGTON.

ADJUSTABLE ATTACHMENT FOR LOUD-SPEAKER UNITS.

Application filed May 29, 1926. Serial No. 112,472.

My invention relates to adjustable attachments for loud speaker units and certain objects of the invention are to provide an attachment in combination with the armature of a loud speaker unit wherein the sound is relayed from the armature link over a resilient bridge to a link extension that is disposed between said armature link and the bridge support to give a leverage whereby the sound is greatly improved in volume, power and tone. Further objects are to provide adjustable means in cooperative relation with the resilient bridge and armature link whereby the armature may be pivotally adjusted between the polar extensions of the unit. Another object is to provide stop means for the adjusting screw that serves as a safety device for preventing undue strains to the armature and its connections.

With the above and other objects in view which will appear as the description proceeds, the invention consists of the novel construction, adaptation, combination and arrangement of parts hereinafter described and claimed. These objects are accomplished by devices illustrated in the accompanying drawings, wherein:

Figure 1 is a view in elevation of a loud speaker unit with certain parts broken away and showing my device attached thereto;

Fig. 2 is an enlarged sectional view taken substantially on a broken line 2, 2 of Fig. 1;

Fig. 3 is a top plan view of Fig. 1 with the cone portion removed; and

Fig. 4 is a sectional view taken on a broken line 4, 4 of Fig. 1.

Referring to the drawings throughout which like reference numerals designate like parts, the numeral 5 indicates a cone frame having a support 6 mounted thereupon which is provided with an extension 7. A resilient bridge member 8 is secured to the upper side of said extension member and a flat spring 9 secured by adjusting screws 10 engages said bridge member for reasons presently set forth.

A link extension 11 is fastened to the bridge 8 at a point 12 and a fragmentary portion of a cone 13 is shown mounted on the remote end of said link extension. The armature link 14 is secured to the outer end portion of said bridge at a point 15 and extends through a hole 16 in the cone support 5 and alongside one of the U-shaped polar

extensions 17 and is fastened at its other end portion 18 to one end of the armature 19. Said armature is centrally pivoted at 20 between said polar extensions and windings 21 thereon as clearly shown in Fig. 2 of the 60 drawings.

The polar extensions 17 are secured to end portions of the permanent magnet 22 by screws 23 and one of said extensions is riveted at 24 to the cup 16^a whose flange is secured to the cone frame 5 by screws 25. A small U-shaped spring 26 is arranged to yieldingly engage the free end of the armature 19. The immediate foregoing features are embodied in the device known as the 70 Baldwin unit and form no part of the present invention except in so far as they may enter into novel combination therewith. It will be understood that my invention is not limited to a combination with the Baldwin 75 unit and that same may be used in connection with any loud speaker unit to which it might be adapted.

A casing 27 may be used to enclose the unit as a whole and an adjusting screw 28 provided with a knob 29 passes through the enclosure of the magnet 22 and through a slot 30 in the cup 16^a. Said screw is threadedly mounted in the cone frame 5 with its end portion projecting therethrough and engaging the outer end portion of the extension 7. 80

It will now be obvious that by turning the adjusting screw 28 in either direction the tension exerted by the spring 9 will cause the resilient bridge 8 to follow the screw. The 90 armature link 14 being secured to said bridge at 15 will likewise be moved back and forth and its other end will move the armature 19 on its pivot point 20. Thus it will be seen that said armature may be pivotally adjusted 95 between the polar extensions 17 and readily brought to a point midway therebetween to give the best vibratory results.

A pin 31 is secured through the end portion of the adjusting screw 28 and its ends 100 are arranged to swingingly engage a projecting portion 32 of one of the screws 25. This arrangement serves as a stop to limit the movement of said adjusting screw and consequently the movement of the armature link 105 14 and armature 19. When said pin reaches the limit of its swing and engages the screw 32 on either side said armature will impinge the edge portions of the polar extensions 17 and can go no further. Undue or accidental 110

strains will therefore be prevented from affecting the armature and its associated parts.

Referring particularly to Fig. 1, the bridge arrangement shown therein is the most important part of my invention. The point where the bridge 8 is supported by the adjusting screw 28, as designated by the numeral 33, serves as a fulcrum, and the bridge from this point outwardly serves as a lever and is actuated by the vibratory function of the armature link 14 in moving the link extension 11 at the point 12. The resilient portion of said bridge extends substantially from the point 12 to the fulcrum 33. It is of primary importance that the portion of the bridge from the point 12 to the point 15, where said armature link is fastened thereto, shall be stiff and inflexible. As shown in the drawings, I have channeled this portion of the bridge to give the required stiffness, although same may be made flat and straight or in any other form as long as the stiffness is provided between these two points.

In the foregoing leverage arrangement as long as the point 12 where the leverage action is transmitted to the link extension 11 lies between the fulcrum 33 and the point 15 where the vibratory force is applied the amplitude of the vibrations in said link extension will, of course, be proportionally reduced. At the same time the power of the vibrations in said link extension will be greatly increased and the volume of the sound issuing from the cone 13 will, of course, be correspondingly increased. This appears to be due to the fact that the lesser but stronger vibrations correspond more closely in pitch with the nature of the cone or diaphragm material. The increase in volume, which is more than double, may be tuned down if desired and will improve the quality of the tone a corresponding amount.

Having thus described my invention, it being understood that this disclosure is intended as an illustration to show one means of reducing my principle to practice and that such changes may be resorted to as are within the scope and spirit of my invention, what I claim and desire to secure by Letters Patent of the United States is:—

1. An adjustable attachment for loud speaker units comprising a resilient bridge fixedly mounted at one of its ends, the other end connected to the armature link, a link extension secured to said bridge intermediately of said support and armature link connection, said armature pivotally disposed between its polar extensions, adjust-

ing means adapted to pivotally move the armature, and the portion of the bridge between said link extension and armature link of inflexible construction.

2. An adjustable attachment for loud speaker units comprising a resilient bridge mounted at one end on a fixed support, the other end connected to the armature link, a link extension secured to said bridge intermediately of said support and armature link connection, said armature pivotally disposed between its polar extensions, adjusting means for said bridge adapted to pivotally move the armature through its link connection, the resilient portion of said bridge disposed between the point of contact of said adjusting means and the link extension, and the stiff portion of the bridge extending from said link extension to said armature link connection.

3. An adjustable attachment for loud speaker units comprising a resilient bridge mounted at one end on a fixed support, the other end connected to the armature link, a link extension secured to said bridge intermediately of said support and armature link connection, an adjustable spring for said bridge, the armature pivotally disposed between its polar extensions, adjusting means for said bridge adapted to pivotally move the armature through its link connection, the resilient portion of said bridge disposed between the point of contact of said adjusting means and the link extension, and the stiff portion of the bridge extending from said link extension to said armature link connection.

4. An adjustable attachment for loud speaker units comprising a resilient bridge mounted at one end on a fixed support, the other end connected to the armature link, a link extension secured to said bridge intermediately of said support and armature link connection, an adjustable spring for said bridge, the armature pivotally disposed between its polar extensions, an adjusting screw for said bridge adapted to pivotally move the armature by means of its link connection, stop means for said adjusting screw adapted to limit the pivotal movement of the armature, the resilient portion of said bridge disposed between the point of engagement of said screw and the link extension, and the portion of the bridge between said link extension and armature link being inflexible.

In witness whereof, I hereunto subscribe my name this 20th day of May, A. D. 1926.

HAROLD A. SMITH.
